DRY-CHEMICAL FIRE EXTINGUISHER

Robert D. Kahn, Rockville Centre, N.Y., assignor to
Fedtro, Inc., Rockville Centre, N.Y., a corporation
of New York

Filed Dec. 19, 1966, Ser. No. 5,120

Claims priority, application Japan Oct. 1, 1966

Term of patent 14 years

(Cl. D16—2)

FIG. 1.

FIG. 2.

FIG. 1 is an elevational view of a dry-chemical fire extinguisher, the remaining sides being substantially similar; and

FIG. 2 is a top plan view thereof.

I claim:

The ornamental design for a dry-chemical fire extinguisher, substantially as shown and described.
